UNITED STATES PATENT OFFICE.

CARL G. SWEBILIUS, OF NEW HAVEN, CONNECTICUT, ASSIGNOR TO THE MARLIN FIREARMS CORPORATION, OF NEW HAVEN, CONNECTICUT, A CORPORATION OF DELAWARE.

FIREARM.

Application filed July 18, 1923, Serial No. 652,386. Renewed November 17, 1925.

To all whom it may concern:

Be it known that I, CARL GUSTAF SWEBILIUS, a citizen of the United States, residing at New Haven, in the county of New Haven and State of Connecticut, have invented a new and useful Improvement in Firearms, of which the following is a specification.

This invention relates to firearms and has for its object to render easy the cleaning of 10 a firearm.

In certain types of firearms, the ejector is pivoted in a slot in one wall of the receiver and a spring is provided to project one end of the ejector away from the wall 15 to bring it into position to engage a shell to be ejected. When such a gun is being cleaned the ejector often catches on the cleaning tool rendering difficult the cleaning of the gun and sometimes resulting in the 20 breakage of the ejector parts.

The object of this invention is attained by providing means whereby the ejector may be retained substantially within its slot, thereby rendering possible comparatively free passage of a cleaning tool. Furthermore, this arrangement obviates the possibility of the 25 ejector being caught by the cleaning tool and broken off during cleaning of the gun.

Referring now to the drawings, Fig. 1 is 30 a plan view partially broken away of the receiver of a gun embodying the invention; Fig. 2 is a similar view with the ejector held back; Fig. 3 is a vertical section through the receiver; and Fig. 4 is an enlarged 35 detail view of the retaining means.

In one wall of the receiver 10 is a groove within which is received a plate 11 having an aperture 12. An ejector 13 has one end pivotally attached to the plate 11 and is 40 adapted to lie within the aperture 12. A spring 14, attached to the wall of the receiver and lying in the groove therein, is adapted to project the free pointed end 15 of the ejector 13 into the receiver in position to engage a shell to be ejected. As 45 shown in Fig. 1, the ejector assumes the above described position when the gun is taken down or made ready for cleaning. The ejector is thus in the path of a cleaning 50 tool and the cleaning of the gun is rendered difficult.

To overcome this difficulty, a rotatable member 16 is provided at the forward end of the plate 11. This member, while rotatable,

is set sufficiently tight in the plate that it 55 will not rotate from any vibration or friction of the working parts of the gun. The head 17 of the member 16 is of larger diameter than the portion in the plate so that it projects into the aperture 12. A portion of 60 the head, however, is cut away so that, in one position thereof, it does not project into the groove. The shape of the head is apparent from Figs. 1 and 3. The head is provided with a slot 18 to receive a screw 65 driver or the like whereby it may be rotated.

When the gun is ready for firing, the head is in the position shown in Fig. 1 with no portion projecting into the aperture 12. When it is desired to clean the gun, the 70 ejector 13 is forced into the aperture 12 by a rod, or the like, inserted through the ejection opening and the head 17 rotated to bring a portion thereof over the end 15 of the ejector as shown in Figs. 2, 3 and 4. 75 The ejector is thus retained substantially within the aperture 12 and does not interfere with the ready use of cleaning tools. The barrel may thus be readily cleaned from either end. 80

What is claimed is:

1. In a fire-arm, a pivoted ejector, resilient means for projecting one end of said ejector into position to engage a cartridge, and a member adapted to maintain the cartridge engaging end of said ejector in inoperative position. 85

2. In a fire-arm, a pivoted ejector, resilient means for projecting one end of said ejector into position to engage a cartridge, 90 and a rotatable member having a portion adapted to engage the cartridge engaging end of said ejector to maintain it in inoperative position.

3. In a firearm, a receiver having a groove 95 in one wall, a spring pressed pivoted ejector in said groove, and means to maintain said ejector within said groove, said means having no portion projecting beyond the surface of said wall. 100

4. In a firearm, a receiver having a groove in one wall, a spring pressed pivoted ejector in said groove, and a rotatable member having a portion adapted to engage the cartridge engaging end of said ejector to maintain it within said groove. 105

5. In a firearm, a receiver having a groove in one wall, an apertured plate in said

groove, an ejector pivotally mounted in said plate and adapted to be received in said aperture, a spring adapted to project one end of said ejector into said receiver, and means carried by said plate to maintain said ejector within said aperture.

6. In a firearm, a receiver having a groove in one wall, an apertured plate in said groove, an ejector pivotally mounted in said

plate and adapted to be received in said aperture, a spring adapted to project one end of said ejector into said receiver, and a rotatable member having a portion adapted to engage said ejector to maintain it within said aperture.

In witness whereof, I hereunto affix my signature this 22d day of May, 1923.

CARL G. SWEBILIUS.
